United States Patent Office

Des. 195,482
Patented June 18, 1963

195,482

GRILLE

Edward C. Hallock, 86 Woodland Ave., Summit, N.J.

Filed June 8, 1960, Ser. No. 60,876

Term of patent 14 years

(Cl. D54—2)

FIG.1.

FIG.2.

FIG.3.

FIG.5.

FIG.4.

FIGURE 5 is a cross-sectional view thereof taken on lines 5—5 of FIGURES 3 and 4, and

I claim:

The ornamental design for a grille, as shown and described.
